UNITED STATES PATENT OFFICE.

EDWARD ROACH, OF CHESTERFIELD, ENGLAND.

FLUID-PRESSURE ENGINE.

No. 818,121.

Specification of Letters Patent.

Patented April 17, 1906.

Application filed March 15, 1904. Serial No. 198,271.

To all whom it may concern:

Be it known that I, EDWARD ROACH, a subject of the King of England, and a resident of Chesterfield, in the county of Derby, England, have invented certain new and useful Improvements in Fluid-Pressure Engines or Machines, of which the following is a specification.

This invention has reference to steam and other fluid-pressure engines or machines; and it consists of certain improvements herein-after described whereby the speed of the pistons of engines or machines is decreased without reducing the number of revolutions or strokes in a given time and also decreasing the size and cost and the space occupied.

The invention will be described with the aid of the accompanying drawings, in which—

Figure 1 is a sectional elevation of the engine, and Fig. 2 is an outside elevation of same. Fig. 3 is a longitudinal section through the cylinder; and Fig. 4 is a cross-section through the cylinder, taken at X X, Fig. 3.

25 In the drawings, *a* represents the motor-chamber in which the piston works, and *b* is the piston.

c is the fulcrum-shaft to which the piston is connected, and *d* is the main or crank shaft 30 of the engine.

The piston *b* is mounted—that is, fixed—on the fulcrum-shaft *c* and passes out through stuffing-boxes *e* on the ends of the chamber *b*. The chamber *a*, in which the piston works, 35 is in the general form of a segment of a circle, and the piston *b* vibrates about the axis of the shaft *c* in this chamber.

Steam is distributed to and from the opposite sides of the piston *b* through inlet and 40 exhaust ports *f g* in one end of the chamber *a*, by valve *h* in the casing *i*, and worked by an eccentric *j* and valve-rod *k*.

The fulcrum or piston shaft *c* is at the apex *a'* of the segmental chamber *a*, and it makes 45 a steam-tight joint with this portion of the chamber, and round its edge where it works in connection with the ends and bottom of the chamber *a* it is provided with a spring or other packing *p* of any suitable kind.

50 Motion is transmitted from the piston-shaft *c* to the crank-shaft *d* through an arm or lever *l*, fixed on the end of said shaft, and a connecting-rod *m* on the end of the arm *l* and working at its opposite end on the disk or

crank *n* on the shaft *d*. If desired, there 55 may be two of the arms *l*, one on each end of the shaft *c*, and a connecting-rod from each of these arms for transmitting motion to the main shaft *d*. In the case shown the chamber *a* is arranged with its apex uppermost; 60 but, if desired, it may be inverted and the apex end or portion attached to the bed-plate of the engine.

In action the piston *b* is oscillated to and fro by the action of the steam or other fluid 65 admitted to and exhausted from the chamber *a* to the opposite sides of the piston, such distribution of steam being effected by the valve *h* and steam and exhaust ports of *f* and *g*, and this motion is transmitted to the crank 70 or cranks or disk or disks on the shaft *d* by the connecting rod or rods *m*, and thus the rotation of the crank-shaft is produced by the vibration of the piston *b*.

If desired, the outside arm or arms *l* may 75 have connected with it or them a guide for giving it support, especially in cases for transmitting large powers.

Having now particularly described my invention, what I claim as new, and desire to 80 secure by Letters Patent, is—

In a steam or other fluid pressure engine, a chamber in the general form of a segment of a circle and the piston filling the same from side to side working therein, the fulcrum-shaft *c* connected to the piston, and at the part opposite the piston *b*, working in contact and making joint with the apex *a'* of the chamber, an arm *l* on the shaft *c* outside the chamber, a crank-shaft *d*, a disk *n* mounted 85 thereon, a pin on said disk, a rod *m* connected at one end to said pin and at the other end to the arm *l*, a valve-chamber *i* on one of the upright segment-shaped sides of the piston-chamber, ports *f* leading from the valve-chamber to the piston-chamber, an exhaust-port *g*, a slide-valve in said valve-chamber controlling said ports, an eccentric on the crank-shaft *d* and connections therefrom to the slide-valve for controlling the same, sub- 90 substantially as described.

In witness whereof I have hereunto set my hand in presence of two witnesses.

EDWARD ROACH.
